UNITED STATES PATENT OFFICE.

LOUISE ROBADEY-MARGOT, OF GENEVA, SWITZERLAND.

HAIR-WAVING TONGS.

Application filed May 31, 1927, Serial No. 195,526, and in Switzerland June 2, 1926.

My invention relates to hair waving tongs, of which the accompanying drawing sheets illustrate different constructional embodiments.

5 Fig. 1 is a plane view, Fig. 2 a front view, and Fig. 3 a sectional view, along the line III—III of Fig. 1 of the first constructional embodiment. Figs. 4, 5 and 6 refer to a second, and Figs. 7, 8, 9 and 10 to a third constructional embodiment, Fig. 7 being a side view, Fig. 8 a plane view, and Figs. 9 and 10 sectional and end views of the latter. Figs. 11, 12 and 13 show a fourth constructional embodiment.

15 The first constructional embodiment according to Figs. 1, 2 and 3 is intended to be previously heated and permits of waving the hair by a short application through the hair. It consists of a flap *a* supporting the shoe *b*, on which two combs *c*₁ and *c*₂, integral with a control lug *c*, are pivoted. These combs are located on either side of the flap and in longitudinal planes perpendicular to it. They make possible the rectilinear motion of a sliding block *d*, the lower side of which is fitted with two rows of teeth parallel to those of the combs *c*₁ and *c*₂, and nearly reaching the upper side of the flap *a*. *e* represents the handle.

20 For waving the hair, the operator heats the tongs, and, once the combs *c*₁ and *c*₂ disengaged, by pivoting, from the flap *a*, conducts the latter through the hair; this having been done, he lets the combs *c*₁ and *c*₂ fall down and moves the sliding block *d* along them. The teeth of the combs *c*₁ and *c*₂ maintain the hair at its end, whilst the teeth *d*₁, while shifting, work on its middle and make it waved.

25 The constructional embodiment according to Figs. 4 to 6 is similar to the above. It permits of waving the hair without previous heating by remaining in the hair for some hours, say, the whole night. It is, accordingly, of a smaller size. The handle *e* has been left out, and the lug *c* superseded by a small projection located on one of the side combs. The slideable comb *f*₂ between the two flaps *a*₁ can be motioned by means of a knob *f*. It is held in position by the rod *g*₁ engaging the notch of the comb and locked by the spring *g*.

The constructional embodiment according to Figs. 7 to 10 has a setting *h* with three

30 combs *h*₁, *h*₂ and *h*₃, between which the combs *i*₁ and *i*₂ are allowed to move; the control device of the latter consists of the rotary knob *k* bearing an arm *l*, permitted of sliding in the holes of two knobs *l*₁ and *l*₂, fastened each to the moving combs *i*₁ and *i*₂; a spring *m* holds the whole contrivance in a fixed position. To one end of the setting *h* are hinged the three flaps *n*₁, *n*₂, *n*₃. The middle flap *n*₂ is located beneath the comb *h*₂ and shows somewhat larger dimensions than the two side flaps. Also this device is intended to be used without previous heating. The flaps are inserted beneath a portion of the hair and the setting *h* with the fixed combs *h*₁, *h*₂, *h*₃ and the slideable combs *n*₁, *n*₂ closed over them. Then the knob *k* is turned whereby the combs *i*₁ and *i*₂ are made to slide in an opposite direction to each other and contrary to the action of the spring *m* till the comb *i*₁ is engaged by a bar and held in position by the spring *i*₄. When the waving has been done the device is removed and the two slideable combs are brought back to their initial position by action of the spring *m*.

35 The constructional embodiment according to Figs. 11 to 13 is similar to that according to Figs. 1 to 3. It consists of a knob *r* for the control of the moving comb, capable of sliding in a groove *s* in the setting and being held in both end positions by the two plate springs *t* and *u*.

I claim:

1. A pair of waving tongs comprising a plain jaw, a toothed jaw carrying two lateral combs, a longitudinally movable member in slideable engagement with the toothed jaw and provided with jaws of teeth parallel with the lateral combs, and means for pivotally connecting the said plain jaw and toothed jaw. 40

2. A pair of hair waving tongs comprising a plain jaw curved in its longitudinal direction, a similarly curved toothed jaw carrying two lateral combs, a longitudinally movable member in slideable engagement with the toothed jaw and provided with rows of teeth parallel with the lateral combs, means for pivotally connecting the said plain jaw and toothed jaw, and means for maintaining the said movable member at the end of its stroke. 100

3. A pair of hair waving tongs comprising a plain jaw having a plurality of spaced parallel flaps, a toothed jaw carrying two lateral

combs, the said flaps being arranged between the two lateral combs, longitudinally movable members in slidable engagement with the toothed jaw, each of the said members consisting of a row of teeth parallel with the lateral combs and extending between two adjacent flaps, means for pivotally connecting the said plain jaw and toothed jaw,

means for simultaneously moving two adjacent movable members in opposite direction to each other, and means for maintaining the said movable members at the end of their stroke.

In testimony whereof I affix my signature.

LOUISE ROBADEY-MARGOT.
